UNITED STATES PATENT OFFICE.

RICHARD J. TUGWELL, OF MAYWOOD, ILLINOIS.

DESIGN FOR A CASING FOR COMBINED ILLUMINATED HOUSE-NUMBERS AND DOOR-BELL PUSH-BUTTONS.

No. 40,131.

Specification for Design.

Patented July 6, 1909.

Application filed May 3, 1909. Serial No. 493,752. Term of patent 3½ years.

To all whom it may concern:

Be it known that I, RICHARD J. TUGWELL, a citizen of the United States, residing at Maywood, in the county of Cook and State of Illinois, have invented a new, original, and ornamental Design for a Casing for a Combined Illuminated House-Number and Door-Bell Push-Button, of which the following is a specification, reference being had to the accompanying drawing, forming part thereof.

Figure 1 is a front view, and Fig. 2 a side view of a casing showing my new design.

The casing shown in the drawings has at the front of its upper portion an orifice A for

the push button, and the curved surface B at the front central portion of the casing represents a translucent material adapted to receive the house number, behind which, within the casing, is intended to be placed an electric light to cause the display of the number.

I claim:

The ornamental design for casing for combined illuminated house number and door bell push button, as shown and described.

RICHARD J. TUGWELL.
